United States Patent

Des. 236,808
Patented Sept. 16, 1975

236,808

THREAD CANISTER

Philippe Hardy-The McLain, Columbia, S.C., assignor to
Shakespeare Company, Columbia, S.C.

Filed Sept. 6, 1973, Ser. No. 394,753

Term of patent 14 years

Int. Cl. D9—03

U.S. Cl. D9—216

FIG. 1 is a perspective view of a thread canister showing my new design;

FIG. 2 is an elevational view; and

FIG. 3 is a top plan view thereof.

I claim:

The ornamental design for a thread canister, as shown.
